UNITED STATES PATENT OFFICE.

MARTIN LUTHER WADE, OF MARLOW, OKLAHOMA.

BROOM-CORN TABLER.

1,267,019.

Specification of Letters Patent. Patented May 21, 1918.

Application filed May 26, 1917. Serial No. 171,256.

To all whom it may concern:

Be it known that I, MARTIN LUTHER WADE, citizen of the United States, residing at Marlow, in the county of Stephens 5 and State of Oklahoma, have invented certain new and useful Improvements in Broom-Corn Tablers, of which the following is a specification.

This invention relates to a broom corn 10 tabler and has for its object the production of a simple and efficient mechanism which will throw the broom corn upon the tabler as the machine is moved along the field between the rows of corn.

Another object of this invention is the 15 production of a simple and efficient means for gripping corn stalks and throwing the broom corn upon the tabler.

With these and other objects in view, 20 this invention consists of certain novel constructions, combinations and arrangements of parts as will be hereinafter more fully described and claimed.

In the drawings:

Figure 1 is a side elevation of the machine.

Fig. 2 is a bottom plan view thereof.

Fig. 3 is a central longitudinal section.

Fig. 4 is a section taken on line 4—4 of

Fig. 1.

Fig. 5 is a detail perspective of one of the tabling arms or members.

Fig. 6 is a perspective view of one of the brackets for supporting the tabling arms.

By referring to the drawings, it will be 35 seen that 1 designates the table which comprises an elongated body tapering toward its rear end 2. An idle wheel 3 supports the rear end of the table 1 upon the stand- 40 ard 4.

A plurality of axle supporting members 5 are secured to the end face of the body and engage or support the axle 6. This axle 6 carries a plurality of driving wheels 45 7 which driving wheels are provided with suitable cleats 8 upon the periphery thereof for facilitating the gripping of the wheels into the corn over which the device may be passing.

A plurality of hanger brackets 9 are 50 secured to the sides of the table 1 and these hanger brackets are connected to the axle supporting members 5 for bracing the same. A tongue or draft bar of suitable construc- 55 tion as shown in Fig. 1 of the drawings is secured to the supporting members 5.

A sprocket wheel 12 is carried by the shaft 6 and a sprocket chain 13 passes over this sprocket wheel 12 and also passes over the sprocket wheel 14 carried by the shaft 60 15. This shaft 15 is journaled upon the journal blocks 15' carried by the side rails 16 of the table 1.

An inverted substantially U-shaped bracket 18 is secured at one end to the side 65 rail 16 of the table as illustrated in Fig. 4 of the drawings and the driving shaft 15 passes through the depending portion 22 of the bracket 18 and has its opposite ends journaled in the depending journal blocks 70 15'.

Each of these brackets 18 is provided with a horizontally extending portion which horizontally extending portion is provided with a vertically extending journal 17 75 through which passes a vertically extending shaft 20. Each of these shafts 20 carries a bevel gear 21 at its lower end which meshes with a bevel gear 23 carried by the shaft 15. The bracket 18 is also provided with a depending portion 22 above mentioned through which the shaft 15 also passes. This structure is clearly illustrated in Figs. 4 and 6 of the drawings.

A head 24 is carried by the upper end 85 of the shaft 20 and is provided with a plurality of oppositely arranged curved fingers 25, which fingers are adapted to project beyond the table 1 and lift the corn stalks upon the table 1.

From the foregoing description, it will 90 be seen that the operation of the device is as follows:

As the machine moves forwardly, the wheels 7, of course, will be rotated, thereby rotating the sprocket wheel 12 which in turn will rotate the shaft 15 and also rotates the shafts 20. These shafts 20 by being rotated will strike the fingers 25 and cause the broom corn to be swung upon the 100 tabler.

As shown in Fig. 1, a suitable seat 26 is mounted upon the forward end of the table 1.

What is claimed is:

A broom corn tabler of the class described comprising a table, wheels supporting said table, an axle carried by said wheels, a sprocket wheel carried by said axle, a shaft carried by said table, a sprocket carried 105 by said shaft, a chain for driving said sprocket, journal blocks carried by the

sides of said table and receiving the ends of said shaft, said table provided with side rails, an inverted substantially U-shaped bracket secured to the under face of said table and abutting at one end against said side rails, said bracket provided with a vertically extending journal extending through said table, a vertical finger-carrying shaft extending through said journal, said bracket provided with a depending end having a journal portion thereon for receiving said

first mentioned shaft, and means carried by said shafts for rotating said finger-carrying shaft, as said first mentioned shaft is operated.

In testimony whereof I affix my signature in the presence of two witnesses.

MARTIN LUTHER WADE.

Witnesses:

L. Z. BROWN,
J. F. McGEEHEE.
